US00D574921S

(12) **United States Design Patent**
Massey

(10) **Patent No.:** **US D574,921 S**
(45) **Date of Patent:** **** Aug. 12, 2008**

(54) **SEWAGE TANK FLANGE**(75) Inventor: **Adrian Massey**, Mount Waverley (AU)(73) Assignee: **Environment One Corporation**,
Niskayuna, NY (US)(**) Term: **14 Years**(21) Appl. No.: **29/249,115**(22) Filed: **Sep. 21, 2006****Related U.S. Application Data**

(63) Continuation of application No. 29/210,528, filed on Aug. 2, 2004, now Pat. No. Des. 529,573.

(51) **LOC (8) Cl.** **23-01**(52) **U.S. Cl.** **D23/206**(58) **Field of Classification Search** **D23/202-205;**
220/561, 565, 587, 532.2

See application file for complete search history.

Primary Examiner—Robin V Webster(74) *Attorney, Agent, or Firm*—Heslin Rothenberg Farley & Mesiti P.C.(57) **CLAIM**

The ornamental design for a sewage tank flange, as shown and described.

DESCRIPTION

FIG. 1 is a perspective view of a sewage tank flange in accordance with the new design;

FIG. 2 is a front elevational view thereof; a rear elevational view being a mirror image thereof; and,

FIG. 3 is a bottom view thereof.

The broken lines in the drawings are for illustrative purposes only and form no part of the claimed design.
